Primary Examiner — Mark Goodwin(74) *Attorney, Agent, or Firm* — Michael Best & Friedrich LLP(57) **CLAIM**

I claim the ornamental design for an agricultural tillage implement, as shown and described.

DESCRIPTION

FIG. 1 is a first perspective view of an agricultural tillage implement showing our new design.

FIG. 2 is a second perspective view of the agricultural tillage implement shown in FIG. 1.

FIG. 3 is a third perspective view of the agricultural tillage implement shown in FIG. 1.

FIG. 4 is a fourth perspective view of the agricultural tillage implement shown in FIG. 1.

FIG. 5 is a first plan view of the agricultural tillage implement shown in FIG. 1.

FIG. 6 is a second plan view of the agricultural tillage implement shown in FIG. 1.

FIG. 7 is a first elevation view of the agricultural tillage implement shown in FIG. 1.

FIG. 8 is a second elevation view of the agricultural tillage implement shown in FIG. 1; and,

FIG. 9 is a cross-sectional view of the agricultural tillage implement shown in FIG. 1, viewed along section 9-9.
